UNITED STATES PATENT OFFICE

WALTER D. BUTZ, OF NORRISTOWN, PENNSYLVANIA

DESIGN FOR A STOCKING

Application filed December 4, 1929. Serial No. 33,642. Term of patent 14 years.

To all whom it may concern:

Be it known that I, WALTER D. BUTZ, a citizen of the United States, residing at Norristown, in the county of Montgomery and State of Pennsylvania, have invented a new, original, and ornamental Design for Stockings, of which the following is a specification, reference being had to the accompanying drawing, forming part thereof.

I claim:

The ornamental design for a stocking, as shown.

WALTER D. BUTZ.
